UNITED STATES PATENT OFFICE.

AARON MARTIN HAGEMAN, OF BLOOMFIELD, NEW JERSEY, ASSIGNOR TO WESTINGHOUSE LAMP COMPANY, A CORPORATION OF PENNSYLVANIA.

METHOD OF AND MEANS FOR INTRODUCING POTASSIUM OR OTHER VAPORS IN LAMPS.

Application filed July 23, 1923. Serial No. 653,116.

To all whom it may concern:

Be it known that I, AARON MARTIN HAGEMAN, a citizen of the United States, and a resident of Bloomfield, in the county of Essex and State of New Jersey, have invented a new and useful Improvement in Methods of and Means for Introducing Potassium or Other Vapors in Lamps, of which the following is a specification.

10 This invention pertains to electric lamps of the gas-filled type and has more particular reference to a method of and a means for the introduction of a free alkali metal into neon lamps.

15 It is an object of the invention to provide a practical and efficient method of introducing an alkali metal such as potassium into an electric discharge device or other evacuated or gas-filled container to act as a getter and to reduce the electrode voltage drop.

It is another object to devise a means by which an alkali metal such as potassium may be easily and readily introduced within an evacuated or gas-filled container.

25 Other objects will become apparent from the description and claims and from the drawing in which the figure is an elevation of a discharge lamp of the gas-filled type embodying the invention.

30 It is well known that the starting and operating voltages of neon or other gas-filled glow lamps may be much reduced by the introduction of an alkali metal therein. The best results have been obtained by the

35 use of potassium in vapor form, which seems to increase the ionization between or the electron discharge of the metal electrodes as well as to reduce the resistance of the gap between them. This is, however, but a 40 theory of the principal cause of the peculiar phenomenon that takes place upon the introduction of a vapor of an alkali metal into this type of discharge lamp.

Considerable difficulty has been encountered in using metals of the class of potassium since their low melting points and susceptibility to oxidation or combination with other metals or compounds destroys their usefulness as voltage drop reducers and

clean-up agents and renders their manipulation by the usual methods and means extremely dangerous. Potassium for instance with a melting point of 62° C. will readily take fire from contact with the human skin making it necessary to use costly apparatus and methods to properly handle it.

I find that an amalgam of mercury and potassium may be so prepared in the solid state that a condition of reduced activity is reached in which condition, the amalgam may be cast into pellets of a desired size and shape and introduced into the lamp or other device before the potassium can react with the moisture and gases in the surrounding atmosphere. Such an amalgam may be prepared by heating pure mercury to from 65° to 70° C., which is above the melting point of potassium (62° C.) and, by means of a pair of tweezers, immersing small pieces of clean and pure potassium beneath the surface of the heated mercury. The potassium will melt and rapidly form a liquid potassium-mercury amalgam with the potassium thoroughly and homogeneously incorporated with the mercury. Stirring may help to completely diffuse the two metals. By this method it was found possible to obtain an amalgam having a softening point as high as 110° C.

Amalgams containing varying percentages of potassium may be readily prepared by this method but I may prefer to use an amalgam containing 2% of potassium for neon glow lamps. Difficulty may be experienced in preserving the amalgam in pellet form in the open atmosphere although it may be readily introduced within a lamp and maintained in a solid condition during the process of manufacturing the lamp if reasonably protected from heat during the sealing-in and exhaust operations.

In introducing the amalgam into the lamp I prefer to secure it to a portion of the interior structure in some suitable manner. For instance as is illustrated in the drawing, I may secure a cup 2 of suitable material to the terminal of one of the non-contacting electrodes 4, 6, which are se-

cured in the usual manner to lead-in wires 8 and within the usual bulb 10. The cup may be made of copper or any material not readily attached by the potassium, suitable for the purpose and is attached to the end of the electrode in any desired manner. The cup may be packed or filled with the prepared amalgam and may be positioned in any manner desired with respect to the sealing-in and exhausting operations as the mercury of the potassium amalgam readily amalgamates with copper and adheres to the cup, if the cup be made of such metal as copper, with sufficient tenacity to prevent it from being jarred out. Any heat reflected from the sealing-in or tipping operations toward the cup is conducted over the wire electrodes, which act as a heat shield, and thereby dissipate the heat.

After the lamp or other vessel is exhausted, neon or other gas or gases, suitable for the purpose, may be introduced in any manner known in the art. The alkali metal is volatilized by application of heat from the exterior or by connecting the electrodes across a source of power of sufficient potential to cause sufficient heating of the electrodes to volatilize it. Other methods of volatilizing the alkali metal such as by high frequency inductive heating of the amalgam by eddy currents induced therein, may be resorted to as will be readily apparent. It may be preferable to cold exhaust the lamp and if this be done, it may be necessary to treat out any occluded gases from the electrodes prior to their assembly in the lamp structure.

While this invention has been described particularly with reference to the introduction of potassium into neon lamps, it is to be understood that it is not so limited but broadly comprehends the manipulation of the alkali metals in such manner that they may be readily introduced into evacuated or gas-filled containers of various types and readily handle for any desired purpose.

I do not limit myself therefore to the particular form or structure shown as many modifications of the invention will present themselves without departing from its spirit or from the scope of the appended claims.

55 What is claimed is:

1. The method of introducing a free alkali metal into an electrical discharge device which comprises preparing a relatively high melting point amalgam of said metal and introducing the amalgam in the said device in contact with a metal part of the device.

2. The method of introducing the vapor of an alkali metal into an electrical discharge device comprising introducing a relatively high melting point amalgam of

said metal into said device in contact with a metal part thereof and vaporizing said alkali metal.

3. The method of introducing the vapor of an alkali metal into an electrical discharge device comprising introducing an amalgam of said metal having a relatively high melting point into said device in contact with a metal part thereof, exhausting said device and vaporizing said alkali metal. 75

4. The method of introducing an alkali metal into a discharge device consisting in amalgamating said metal and applying the amalgam at room temperature to a metal part of the device to which it readily adheres. 80

5. The method of introducing an alkali metal into an electric device in a solid state which consists in mixing said metal with mercury and applying the mixture as an amalgam to a metal part of the device. 85

6. The method of introducing an alkali metal into a discharge device consisting in applying said metal in the form of a mercury amalgam to a copper body and introducing the copper body into the device. 90

7. The method of introducing potassium into a discharge device having metal electrodes consisting in attaching a copper body to one of said electrodes and applying potassium in the form of an amalgam to the copper body. 95

8. The method of reducing the starting voltage of gas-filled discharge devices which comprises positioning an amalgam of an unstable metal on a metal portion of the device in proximity to the path of discharge and causing a discharge whereby said unstable metal is volatilized. 100

9. The method of reducing the starting and operating voltages of gas-filled discharge devices having solid electrodes comprising, supporting an amalgam of an unstable metal within said device, from a metal part thereof in the vicinity of the path of discharge and causing a discharge whereby said unstable metal is volatilized. 110

10. A commercially unfinished gas-filled electric discharge device having solid electrodes and means including an alkali metal in a relatively stable state attached to one of said electrodes by mercury and cooperative therewith whereby said alkali metal is rendered unstable upon the passage of a current between said electrodes. 120

11. The method of introducing an alkali metal into a discharge device which consists in forming an alloy of the metal which will adhere to metal at normal temperatures and applying said alloy to a metal part of said device prior to the sealing of said part into the device. 125

12. The method of introducing an alkali metal into an evacuated container which consists in forming an amalgam of the 130

metal, applying the amalgam to another metal with which the mercury of the amalgam readily amalgamates and introducing said last mentioned metal into the device.

5 13. The method of introducing an alkali metal into an electrical discharge device consisting in applying said metal in the

form of a mercury amalgam to metal parts of the device to which the amalgam readily adheres.

In testimony whereof, I have hereunto subscribed my name this 21st day of July 1923.

AARON MARTIN HAGEMAN.
